Primary Examiner — Susan Bennett Hattan*Assistant Examiner* — Bryan Reinholdt, Jr.(74) *Attorney, Agent, or Firm* — Dority & Manning, P.A.(57) **CLAIM**

The ornamental design for a beverage holder, as shown and described.

DESCRIPTION

FIG. 1 is a perspective view in a fully assembled configuration showing my new design;

FIG. 2 is a top view in a fully assembled configuration thereof;

FIG. 3 is a front view in a fully assembled configuration thereof;

FIG. 4 is a right side view in a fully assembled configuration thereof;

FIG. 5 is a front view in a partially assembled configuration thereof;

FIG. 6 is a front plan view in an unassembled configuration thereof; and,

FIG. 7 is a rear plan view in an unassembled configuration thereof.

The broken line portion of the drawings represents stitching that forms no part of the claimed design.
